UNITED STATES PATENT OFFICE.

HERMAN S. STERNBERGER, OF PIQUA, OHIO.

FOLDING DRESS-PILLOW.

SPECIFICATION forming part of Letters Patent No. 319,340, dated June 2, 1885.

Application filed January 2, 1885. (No model.)

To all whom it may concern:

Be it known that I, HERMAN S. STERNBERGER, of Piqua, in the county of Miami and State of Ohio, have invented a new and useful 5 Improvement in Folding Dress-Pillows, which improvement is fully set forth in the following specification and accompanying drawings, in which—

Figure 1 is a perspective view, with the 10 upper side partly broken away, of my improved folding dress-pillow; Fig. 2, a perspective view of the frame-work; Fig. 3, a perspective view of the device when closed up; Fig. 4, a perspective view of the axial piece 15 and one of the rib-sections, and Fig. 5 a perspective view of a modification of the axial piece as shown in Fig. 4.

The present invention relates to an improvement 20 in folding dress-pillows, consisting of the central axial piece having a series of semi-circular ribs covered with any suitable material, and so disposed that, when opened, two of the said ribs may be somewhat parallel and secured together by means of clips, while the 25 other ribs may be at right angles with each other, and to the first ones, thus forming a rectangular-shaped pillow, while at the same time by loosening the clips and securing the parallel ribs together they may be moved 30 around to one side of the axial piece, and thus fold up the device, all of which will now be fully set forth in detail.

In the accompanying drawings, A is a cylindrical piece having openings B centrally at 35 each end, and outwardly, near the periphery, a series of smaller openings, C, preferably five in number. I next provide a semi-elliptical piece of wire, D, having the ends E turned inwardly, forming hooks, and placed within the 40 openings C at opposite ends of the cylindrical piece A, as shown in Fig. 4.

A modification of the cylindrical piece A is shown in Fig. 5, in which I place the hooks F within the central opening, B. Radiating outwardly from this axial piece A, I provide semi-elliptical ribs, and preferably five in number. Two of these ribs, G and H, I design to be somewhat parallel, forming a pair, while the other three radiate singly at right angles

50 to each other of the pair G H. From these ribs I stretch canvas or other suitable material, J, as shown in Fig. 1.

Outwardly upon one of the pair of ribs, G, I provide a wire hook or catch, K, so that when the device is opened up and the canvas 55 stretched, as shown in Fig. 1, the ribs G and H will be nearly parallel to each other and close together, and be held in that position by means of said catch K. I desire to provide a pair of these catches K on opposite sides of 60 the said ribs, so as to hold them securely together.

When it is desired to fold up the device, the 65 catches K are released, and the ribs G and H turned from each other around the axial piece A and brought close together oppositely, thus placing it in a small compass, as shown in Fig. 3. When it is desired for use, the ribs are again turned back, so as to radiate outwardly 70 from the center, and the ribs G and H secured in position by means of catches K.

I do not claim a central piece having arms pivotally hooked thereto, as shown in my application for Letters Patent No. 159,754.

What I claim is—

1. In a folding pillow, a series of radiating hinged ribs, two of them brought close together and so disposed as to swing around and thus fold up the device, in combination with a catch, K, substantially as herein set forth. 80

2. In a folding pillow, a cylindrical piece having centrally at the ends circular openings, and outwardly, near the periphery, a series of openings to receive therein a hook, substantially as herein set forth. 85

3. In a folding pillow, a series of semi-elliptical ribs, with the ends bent inwardly and resting within openings in the heads of the cylindrical piece, in combination with the cylindrical piece, substantially as herein set forth.

In testimony that I claim the foregoing I have hereunto set my hand, this 28th day of November, 1884, in the presence of witnesses.

HERMAN S. STERNBERGER.

Witnesses:

WILLIAM MORROW,

ALLEN L. MARSHALL.
